PEDESTAL

William H. Mahoney, Hingham, Mass.

Application June 20, 1936, Serial No. 86,287

1 Claim. (Cl. 72—101)

My present invention relates to pedestals and more particularly to mail box pedestals;

The principal object of my invention is an improved pedestal for mail boxes and the like;

5 Another object is a device of the character above described having novel means for fastening the mail box to the pedestal;

Still another object is a novel means of mounting a name plate on the pedestal in combination 10 with the strengthening bar separating the forked upper end of said pedestal, and

Other objects and novel features comprising the construction and operation of my device will appear as the description of the same progresses.

15 In the drawing illustrating the preferred embodiment of my invention,

Fig. 1 is a side elevation of the pedestal;

Fig. 2 is another side elevation of the pedestal taken at ninety degrees to Fig. 1;

20 Fig. 3 is an enlarged cross-section taken on the line 3—3 of Fig. 1, and particularly showing the method of producing an anchoring means for nailing a mail box to the top of the pedestal, and

Fig. 4 is another enlarged cross-section taken 25 on the line 4—4 of Fig. 1.

Referring more in detail to the drawing, 30 10 indicates a vertical base portion of the pedestal, a portion of which adjacent the lower end is usually set in the ground. Connecting with the lower portion 10 is a forked or yoked top portion comprising two mail box supporting members 11 and 12. Separating the forked members 11 and 12, and forming a combined support thereto together with a mounting for a name plate is 35 the horizontal bar member 13. This bar member 13 while forming a rigid support for the members 11 and 12 is provided on the front with a recess having a back portion 14, and top and bottom sides 15 and 16 respectively.

40 Within the recess bounded by the sides 14, 15 and 16 I have provided a name plate 17 upon which the name of the owner is placed in any convenient manner, such as affixing prepared letters thereto. The plate 17 may, if desired, be 45 of varying lengths suitable to accommodate the particular name used in any instance or such plate may extend the whole length of the bar 13. In the drawing, I have shown the plate extending the whole length of bar 13 but I may 50 make this plate of different lengths to fit the particular name. The plate 17 is preferably made of glass but other material may be used if desired. Covering the plate 17 is a second glass 55 plate 18, the outer surface of which is flush with the outer side of the bar 13. Both plates 17 and

18 are sealed in the recess bounded by the walls 14, 15 and 16 either when the pedestal is cast or afterwards making a water tight insert.

When these pedestals are made to order, as is the practice at present, I provide a core in the 5 mold the size of the opening represented by the walls 14, 15 and 16, the length being determined by the name which is to go on the name plate. The core may consist of the two plates 17 and 18 if desired but preferably a separate core is 10 used, the plates 17 and 18 being inserted after the pedestal has been molded.

In Fig. 3, I have shown my preferred apparatus for anchoring articles, such as mail boxes or the like, to the top of the members 11 and 12. 15

It is important that a pedestal of the type illustrated be provided with a more or less permanent anchorage for articles which may be placed upon it, and that such articles may be removed and substituted for as the case may be. 20 But in order that such articles, as mail boxes or the like, may be mounted in a more or less permanent manner, I have designed the particular anchorage illustrated in the drawing, of which, Fig. 3 is an enlargement of the preferred 25 form. In Fig. 3, it will be noted that I have provided a simple conventional coupling 21 which is threaded to the reinforcement member 22 which strengthens the entire apparatus. The 30 top of the coupling 21 extends to the top surface of the members 12, member 11 being an exact duplicate. In the upper internal threaded portion of the coupling 21, I have inserted a wooden 35 plug 23. The wooden plug 23 is normally made with an outer periphery approximately the same diameter of the root of the threads shown in the coupling 21 and is screwed into the coupling and cut off as shown in Fig. 3. The threads of the coupling hold the wooden plug 23 securely 40 in place. When an article such as a mail box, or other article is mounted upon the pedestal 45 nails may be driven into the wooden member 23 and headed up on the under side. The top of the reinforcing rods 23 provide an anvil face 45 at 24 against which the ends of nails are turned and headed over making it impossible to remove the mail box or other device fixed to the pedestal without cutting off the nail heads and removing the member 23. The material comprising the 50 superstructure of the pedestal is composed of a plastic material preferably concrete, as indicated at 12.

The reinforcement member 22 takes the outline of the pedestal and ends in the members 21 55

which combine to form the anchorage members shown in Fig. 3.

While I have shown my invention in its preferred shape and form yet it is to be understood 5 that I may vary the size and proportions within wide limits without departing from the spirit of the invention.

Having thus described my invention what I claim as new is:

- 10 In a reinforced concrete pedestal for mail-boxes and the like, a mail box anchor construction comprising in combination with a solid re-

inforcement rod, one end of said rod being externally threaded, an internally threaded coupling threaded to the threaded end of said solid rod, the end of said rod forming an anvil surface within said coupling, a threaded plug threaded in the other end of said coupling for the purpose of receiving mail-box connecting members, the said anvil surface being adapted to turn the ends of the said connecting members imbedded in the said plug. 5

10

WILLIAM H. MAHONEY.
